UNITED STATES PATENT OFFICE.

DANIEL C. MULVIHILL, OF HANNIBAL, MISSOURI.

SWITCH STAND AND TARGET.

1,384,148.

Specification of Letters Patent. Patented July 12, 1921.

Application filed December 20, 1920. Serial No. 432,084.

To all whom it may concern:

Be it known that I, DANIEL C. MULVIHILL, a citizen of the United States, and resident of Hannibal, county of Marion, and State of Missouri, have invented certain new and useful Improvements in Switch Stands and Targets, of which the following is a specification, and which are illustrated in the accompanying drawings, forming a part 10 thereof.

The invention relates to switch stands, and has as an object the provision of a stand having means to adjust the throw of the switch rod. A further object is the 15 provision of novel means to operate the target; also means to render it impossible to put the target on its staff in such a manner as to give an erroneous signal.

An illustrative embodiment of the invention is shown in the accompanying drawings, in which—

Fig. 1 is a side elevation of a switch stand, the switch lever being shown in section;

Fig. 2 is a plan view;

Figs. 3 and 4 are side elevations of two forms of levers showing different forms of adjusting means;

Fig. 5 is a horizontal section on line 5—5 of Fig. 1;

Fig. 6 is a detail side elevation of a screw for operating the lever; and

Fig. 7 is a perspective view of a staff.

The switch stand comprises a base plate 10, with a block 11 having a screw-threaded 15 passage through it, and a chamber 12 opening into the passage for the reception of the staff operating pinion. The base plate is designed to be secured to the ties by screws passing through holes, not shown.

The switch rod 13 is adapted, by its reciprocation, to operate the switch. To reciprocate the switch rod a lever 14 is secured to the bifurcated end 15 of the switch rod, as by means of a pin 16. The other end of 45 the lever 14 is pivotally secured by means of a pin 17, between a pair of links 18, which in turn are secured to a lug 19 on the switch block by means of a pin 20, thus constituting a lever of the third class.

To operate the lever 14 a rod 21, having a bifurcated end 22, is secured to the lever by a pin 23. To cause reciprocation of the rod 21 a sleeve 24, having a screw-thread

25 on its exterior adapted to fit the interior screw-thread in the switch block 11, is 55 revolvably mounted thereon, bearing against a shoulder 26 on the rod at one end. A cap 27, retained on the end of the rod 21 by a cotter pin 28 passing through the cap and rod, is provided to prevent the sleeve 24 from 60 moving lengthwise away from the shoulder 26. To revolve the sleeve 24 on the rod 21, a switch lever 29 is fitted to a squared end 30 of the sleeve and retained thereon by means of the cap 27. Revolution of the 65 sleeve 24 will cause reciprocation thereof, carrying with it the rod 21, which is prevented from revolving by its connection with the lever 14.

A connection of the rod 21 to the center 70 of the lever 14 will cause a motion of the switch rod 13 just twice as great as that of the rod 21. With the usual 180° movement of the switch lever 29 the resulting movement of the switch may not always be what 75 is desired. In order to adjust the amount of movement of the switch rod 13, the pivotal point of attachment of the rod 21 to the lever 14 is made adjustable. To this end a block 31, having a hole 32 for the reception 80 of the pin 23, is fitted into an opening 33 in the lever and supported therein by shims 34. The block 31 and shims 34 are retained in the hole 33 by the bifurcations of the end of the rod 21 passing on each side thereof. 85 By shifting the shims from one side to the other of the block 31 its position in the lever, and therefore the movement of the switch rod 13, may be adjusted.

A modified form of adjusting means is 90 shown in Fig. 4, in which form the lever 14' is provided with a hole having a series of equally spaced recesses 35. A circular block 36, having teeth 37 adapted to fit into said recesses in any position of rotation of the 95 block, is provided with an opening 38 for the pin 23, which opening is eccentric to the block. The throw of the lever 14' may be adjusted by rotating the block 36, which block will be retained, like the block 31, by 100 the end of the rod 21.

To operate the target or signal staff 39 it is journaled in the top and in the bottom of the block 11, and has secured thereon a pinion 40, standing in the recess 11 and meshing with worm threads 41 on the surface of 105

the thread 25 of the sleeve 24. To avoid more than the desired 90° rotation of the target staff during the 180° rotation of the sleeve 24, without an objectionable number 5 of teeth in the pinion 40, the threads 41 are placed spirally on the surface of the thread 25, thereby offsetting a portion of the longitudinal movement of the sleeve.

The simple form of signal or target shown 10 is composed of four plates 42, each having flanges 43, 44, at top and bottom, plates 45, 46, being riveted to the top and bottom flanges, respectively, of each plate, thus holding them in a cruciform position with their 15 inner ends spaced to span the rectangular upper end 47 of the staff. The target may be retained on the staff by a cotter pin 48, passed through a hole 49 in the staff just above the lower plate 46.

20 A great defect in switch targets as heretofore constructed is the possibility of their being placed on the staff in a wrong position, thus giving a wrong signal. If not noticed by the switchman the error may cause serious 25 wrecks. Because of this fact it is the usual custom to send a man out to repaint them *in situ*, which is an expensive practice and inefficient since the paint gets dirty before it can harden. To avoid this defect the 30 present invention provides a staff having a rectangular target-receiving portion that is greater in one horizontal dimension than in the other, and the target is made to fit, thus making it impossible to so place it as to give 35 a wrong signal. As a result of this feature targets may be painted and dried in the shop, and a newly painted one may be put in place of the dull one without possibility of error of indication. This feature of the invention 40 is applicable to street marking signs and many other locations.

Minor changes may be made in the physical embodiment of the invention without departing from its spirit.

45 I claim as my invention:—

1. Switch operating means comprising, in combination, a switch rod, a switch stand, a reciprocating member mounted on the stand, means to transmit motion of said member to said rod increased in amplitude, and means to vary the amount of such increase.

50 2. Switch operating means comprising, in combination, a switch rod, a lever of the third class for actuating said rod, means for actuating said lever, and means to adjust the relative length of the arms of said lever.

60 3. Switch operating means comprising, in combination, a switch rod, a lever of the third class for actuating said rod, means attached to the lever for actuating said lever, and means to adjust the point of attachment of said means to the lever.

65 4. Switch operating means comprising, in combination, a switch rod, a stand, a lever

for actuating said rod pivotally connected at one end to said rod and at the other end to said stand, actuating means connected to said lever between its ends, and means to change one of the points of connection of the 70 lever so as to vary the relative length of the arms thereof.

5. Switch operating means comprising, in combination, a switch rod, a stand, a lever for actuating said rod pivotally connected 75 at one end to said rod and at the other end to said stand, actuating means connected to said lever between its ends, and means to change the point of connection of said actuating means to the lever.

6. Switch operating means comprising, in combination, a block having an internally screw-threaded bore therethrough, a screw-threaded member operating in said bore, a switch rod, operative connections between 85 said switch rod and screw-threaded member including throw increasing means, means for turning said screw-threaded member, and means for varying the throw increase caused by said throw-increasing means. 90

7. Switch operating means comprising, in combination, a switch rod, a switch stand, a lever having an opening in its middle portion, said lever pivotally connected at one end to the rod and at the other end to the 95 stand, actuating means for said lever, a block in said opening, means for connecting said block and actuating means, said block adjustable in the opening to vary the position of said connecting means relative 100 to the length of the lever.

8. Switch operating means comprising, in combination, a block having an internally screw-threaded opening therethrough, said opening having a recess in its wall, a screw-threaded member threaded into said opening having worm threads superimposed on its screw-thread, said member adapted to operate a switch, a target staff, a pinion secured to said staff and standing in said recess with 110 its teeth meshing with said worm threads, and means to rotate said screw-threaded member.

9. Switch operating means comprising, in combination, a block having an internally screw-threaded opening therethrough, said opening having a recess in its wall, a screw-threaded member threaded into said opening having worm threads superimposed on its screw-thread, said member adapted to operate a switch, a target staff, a pinion secured to said staff and standing in said recess with 115 its teeth meshing with said worm threads, said worm threads arranged spirally in the same direction as said screw threads to reduce the effect upon the pinion of the travel 120 of said threaded member, and means to rotate said screw-threaded member.

10. In a switch operating device, in combination, a switch rod, a signal shaft, a fixed 130

nut, a screw running in the nut and operatively connected with the rod and having worm threads formed on its screw threads, and a gear fixed to the shaft and engaging 5 the worm threads.

11. In a switch operating device, in combination, a switch rod, a signal shaft, a fixed

nut, a screw running in the nut and being operatively connected with the rod, and having worm threads non-coöperative with the nut, 10 and a gear fixed to the shaft and engaging the worm threads.

DANIEL C. MULVIHILL.
